UNITED STATES PATENT OFFICE.

ROY W. KELLEY, OF DAVENPORT, IOWA, ASSIGNOR TO WESTERN PATTERN & MANUFACTURING COMPANY, OF MOLINE, ILLINOIS, A CORPORATION OF ILLINOIS.

SAD-IRON.

1,155,424.

Specification of Letters Patent.

Patented Oct. 5, 1915.

Application filed August 14, 1914. Serial No. 856,799.

To all whom it may concern:

Be it known that I, ROY W. KELLEY, a citizen of the United States, residing at Davenport, in the county of Scott and State 5 of Iowa, have invented new and useful Improvements in Sad-Irons, of which the following is a specification.

The present invention has reference to sad-irons, and more particularly to sad- 10 irons of the gas-heated type.

It proposes certain improvements, hereinafter specified at length, in or relating to the construction of the body of the iron, whereby the mixture of air and gas is caused 15 to travel in a tortuous path through the interior of the iron, and concentrated at the point of the iron, where most desired, thus insuring a rapid and thorough heating, while, at the same time, the danger of the 20 hands of the operator, and the material operated upon, becoming burned by the escaping heat is avoided.

An embodiment of the invention is illustrated in the accompanying drawing, in 25 which:—

Figure 1 is a longitudinal, vertical section, taken centrally through the iron; Figs. 2 and 3 are horizontal and vertical sections, taken, respectively, on lines 2—2 and 3—3, 30 Fig. 1; and Fig. 4 is a perspective view of the deflector.

As shown in said drawing, the improved iron consists of a hollow body portion 5, open at its rear end or heel, a top plate 6, provided with a suitable handle 7, and a heel plate 8. The aforesaid body 5 has the upper portion of each of its side walls formed with an open-topped, longitudinal chamber 9, which terminates adjacent to the 35 front and rear ends thereof, the outer section of the wall being provided with a longitudinal series of outlet openings 10, while the inner wall section is made of slightly less height than the said outer section for the purpose of providing an inlet to such chamber.

The top plate 6 is adapted to rest upon the upper face of the body 5, and is detachably secured to the latter by means of screws, or 50 other suitable devices 11. It carries upon its under face the deflecting plate 12, represented in Fig. 4, these two plates being preferably connected together by means of the bolts 13 which join the handle 7 to said top plate. The deflector is arranged within the

interior of the body 5, a short distance below the top thereof, and is of slightly less width and length than the said interior space or chamber, in order to permit the heat and products of combustion to pass around its edges, upwardly and over the tops of the inner sections of the body walls, and into the chambers 9, whence they finally escape through the openings 10. To cause the heat to concentrate toward the point of the iron, the deflector is inclined forwardly and downwardly, as shown in Fig. 1, and is centered with respect to the top plate by means of a series of upstanding lugs or projections 14, of different heights, formed upon its 55 upper face.

The heel plate 8 fits at its side and bottom edges in seats 15 formed in the rear ends of the side and bottom walls of the body 2, and is equipped with a double-ended socket 16, whose inner end projects into the interior of the body and constitutes the burner, while its outer end is threaded and receives therein one end of the mixing tube 17, the other end of the latter being provided with 60 a nipple 18 for the connection of the usual, flexible gas tube, (not shown), thereto. At opposite sides of the socket, the heel plate is formed with vertical slots 19 for the admission of air, and the said inner end of 65 its socket is provided with a covering 20 of wire gauze.

Owing to the construction and arrangement of parts as above described, it will be apparent that the flame is confined entirely 70 within the interior of the iron and the heat, while necessarily concentrated toward the point of the iron by reason of the inclination of the deflector, is caused to pass around the edges of the deflector and into the two 75 chambers 9 before it can escape through the openings 10, so that a rapid heating of the iron is assured. The top plate, as previously stated, is detachably connected to the body of the iron, and when removed, carries 80 with it the deflector, as will be understood. The heel plate is likewise detachable, so that when these two plates are removed the entire interior of the body is open and may 85 be readily cleaned. A screw 21, or other suitable device may be employed to hold the heel plate in place, the stem of such screw fitting in a recessed lip 22 formed at the top of the heel plate and extending into the 90 interior of the body.

I claim:—

- A hollow sad iron having its sides formed with open-topped longitudinal chambers, the outer walls of said chambers having outlet openings extending therethrough at substantially the level of the bottoms of said chambers, and the upper edges of the inner walls of said chambers being below the upper edges of said outer walls, a cover 10 fitted to the top edges of the outer walls and forming passages leading from the interior of the iron over the upper edges of the inner walls and to the tops of said longitudinal chambers, a forwardly and down-

wardly inclined plate arranged within the 15 interior of the iron and having a space between its periphery and the inner walls of said chambers below the upper edges of the latter, and means for directing a combustible medium forwardly into the interior of 20 the iron and beneath said plate.

In testimony whereof I have hereunto set my hand in presence of two subscribing witnesses.

ROY W. KELLEY.
